(57) **CLAIM**

The ornamental design for a ski training apparatus, as shown and described.

DESCRIPTION

FIG. 1 is a perspective view of a ski training apparatus showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is an isolated view on an enlarged scale taken from FIG. 2 of the ski training apparatus.

In the drawings, the broken lines showing a ski illustrate environment and form no part of the claimed design.
